UNITED STATES PATENT OFFICE.

PAUL LEVASSEUR AND ALFRED P. DUMAS, OF FALL RIVER, MASSACHUSETTS.

DESIGN FOR A SOLE-TRIMMING MACHINE.

58,194.

Specification for Design.

Patented June 21, 1921.

Application filed November 15, 1919. Serial No. 338,382. Term of patent 7 years.

To all whom it may concern:

Be it known that we, PAUL LEVASSEUR and ALFRED P. DUMAS, citizens of the United States, residing at Fall River, in the county of Bristol, State of Massachusetts, have invented a new, original, and ornamental Design for a Sole-Trimming Machine, of which the following is a specification, reference being had to the accompanying drawing, forming part thereof.

The figure is a perspective view of a sole trimming machine, showing our new design.

We claim:

The ornamental design for a sole trimming machine, as shown.

PAUL LEVASSEUR.
ALFRED P. DUMAS.
